UNITED STATES PATENT OFFICE.

EDWARD J. COLBY, OF CHICAGO, ILLINOIS.

ELECTRIC ALARM-CLOCK.

SPECIFICATION forming part of Letters Patent No. 370,932, dated October 4, 1887.

Application filed February 23, 1887. Serial No. 228,474. (No model.)

To all whom it may concern:

Be it known that I, EDWARD J. COLBY, a citizen of the United States, residing at Chicago, in the county of Cook and State of Illinois, have invented a new and useful Electric 5 Alarm-Clock, of which the following is a specification.

My invention relates to ordinary alarm-clocks, and has for its object to provide means whereby they may be utilized to close the circuit of an electric battery, and thus cause an electric bell to ring. This object I accomplish by means of the mechanism illustrated in the accompanying drawing, wherein the figure 15 shows the front view of a bell, battery, and ordinary small alarm-clock, with a sectional view through the bell thereof.

A is a bell placed at any convenient locality.

B is a battery, and C is the clock.

20 D is a wire which passes through one leg of the clock to the bell.

E is a wire passing from the battery to the electric bell.

25 F is a wire passing from the battery to the bell on the alarm-clock.

G is the sounding portion of the alarm-clock bell, having an inner tubular portion, H, with a raised ledge, J, thereon.

K is a hammer on the alarm-clock bell.

30 L is the bell-supporting stem issuing from the top of the alarm-clock. M is a ring whereby such clock may be carried, and it is secured by the screw-threads N to the stem L.

O is a cylinder of insulating material which 35 is placed about the stem L. P is a washer of the same material at the base of the cylindrical portion O, bearing on the metallic body of the clock C.

Q is a small washer at the top of the cylinder, lying between the stem R and the sounding portion of the bell G.

The use and operation of my invention are as follows: The clock is set up in the position shown in the drawing, and any number of 45 bells A may be attached thereto, and they may be located in any position. Thus, for instance, if it is desired to use one alarm-clock for the purpose of arousing all of the occupants of a building, it may be done by placing 50 one bell in each sleeping-room and connecting all such bells to the circuit. One end of the circuit upon which these bells are secured is attached to the sounder of the bell on the alarm-clock, and the other end is attached to the 55 metallic portion of the clock proper.

It will be seen that by means of the cylinder O and washers P and Q the metallic portion of the clock proper is insulated from the sounding portion of the bell G, and therefore the circuit is open and none of the bells are sounded. 60 Now, when the alarm-clock has reached the hour at which its alarm is set to strike, the hammer K will strike the sounding portion of the bell G, and will then strike the raised portion J on the cylinder H. Striking this latter 65 portion limits the stroke of the bell-hammer to such an extent that it stops its striking and the hammer rests against the raised portion J, thus closing the connection between the sounder G and the clock C, and thus also completing the electric circuit through the series 70 of bells. This of course immediately sets all of the bells in operation, and they will continue to ring until the circuit is broken.

The alarm-bell on the clock is of the usual 75 form and structure; but the plate J on the bell proper, standing out from the cylinder H of the bell, limits the stroke of the hammer K, so that when the hammer K strikes the piece J the hammer K does not have power or room 80 enough to spring backward, and therefore it remains against the plate J and the circuit is closed, and all the bells on the line will continue to ring until they are switched off or the circuit broken. This compels the sleeping person or the person controlling the device to approach the clock mechanism and by disconnecting some of the parts break the circuit. The hammer K can then be thrown 85 away from the plate J and the device will be 90 ready for operation again as soon as the hour for the automatic setting off of the alarm arrives.

I claim—

1. The combination of an alarm-clock and an 95 insulated bell thereon, said bell having an inward lug or elevated portion which engages the hammer and stops it, so as to close connection between the clock and the bell.

2. The combination of an electric circuit 100 containing an electric bell, with an alarm-clock and an insulated portion thereof, which engages and retains the hammer of the alarm mechanism, so as, when the alarm goes off, to close the circuit, and thus ring the electric bell. 105

EDWARD J. COLBY.
